UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,849, dated October 24, 1893.

Application filed September 19, 1893. Serial No. 485,814. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of lyre-shaped ornaments placed at regular distances apart over the surface of the paper and formed of ornamental scrolls. On opposite sides of each lyre shaped ornament and springing from its base are sprays of flowers, and above it is a thick cluster of flowers, while from its 5 base hangs a floral festoon, as shown in the accompanying drawing.

In the upper portion of the design, which forms the border, a lyre in conjunction with

a trumpet, is suspended by a ribbon from a fleur-de-lis like ornament and branching from the latter are scroll like ornaments from which is suspended a festoon of flowers, ending in sprays which are hung over said scroll like ornaments.

What I claim is—

1. The design for wall paper herein shown and described.
2. In the design for wall paper the border herein shown and described.

Witness my hand this 15th day of September, 1893.

CHARLES BOOZE.
